ADVERTISING SIGN

Edward A. Rutkowski, Euclid, Ohio, assignor to Keeler & Dunkel, Inc., Cleveland, Ohio, a corporation of Ohio

Filed June 3, 1963, Ser. No. 75,196

Term of patent 14 years

(Cl. D1—12)

FIG. 1

FIG. 2

FIG. 1 is a front perspective view taken from one side of an advertising sign showing my new design; and

FIG. 2 is a front perspective view taken from the side opposite that shown in FIG. 1.

The rear is essentially the same as the front of the sign except the rear of the barn portion is plain and unornamented.

I claim:

The ornamental design for an advertising sign, substantially as shown and described.
